UNITED STATES PATENT OFFICE

ELIJAH H. SMITH, OF MORGANTOWN, WEST VIRGINIA

DRESSER

Application filed August 2, 1927. Serial No. 210,111.

This invention relates to furniture and more particularly to a dresser having mirrors so arranged that they may be adjusted to permit a person to obtain either a front, rear or side view.

One object of the invention is to provide a dresser having side portions disposed in such angular relation to each other that the dresser may be placed in a corner of a room 10 and conform to the contour of adjoining walls.

Another object of the invention is to provide a dresser with back mirrors mounted stationary in angular relation to each other 15 and with side mirrors disposed vertically and hingedly connected with forward corner portions of the body of the dresser so that they may be swung towards and away from the front of the dresser and thereby 20 permit persons to obtain views of themselves at different angles.

Another object of the invention is to so mount the movable mirrors that their swinging movement will be limited and the mirrors 25 prevented from being swung into contact with the ends of the body of the dresser and receive blows likely to break the mirrors.

The invention is illustrated in the accompanying drawings, wherein,—

Figure 1 is a perspective view of the improved dresser.

Figure 2 is a view showing the dresser partially in elevation and partially in vertical section.

Figure 3 is a transverse sectional view through the dresser taken along the line 3—3 of Figure 2.

Figure 4 is a fragmentary sectional view illustrating the manner of hingedly mounting the movable mirrors.

The improved dresser includes a body portion indicated in general by the numeral 1 and having side portions 2 and 3 which extend transversely from each other, as clearly 45 shown in Figures 1 and 3 so that the dresser may be placed in a corner of a room with its side portions extended parallel to the walls of the room. Front and rear posts 4 and 5 are provided at the sides of the body 50 which extend its full height and project

downwardly to provide supporting legs to rest upon the floor and retain the body in spaced relation thereto so that the portion of the floor covered by the dresser may be easily cleaned. Similar corner posts 6 and 7 are provided at the intersection of the side portions 2 and 3. Drawers 8 are slidable into and out of the side portions 2 and 3 upon tracks which extend through the body, as shown in Figure 3. The top of the dresser may be formed in one piece, but preferably consists of separate sections 9 which are firmly secured in any desired manner and have their meeting inner ends covered by a strip 10 which serves to conceal the crack 65 between the abutting inner ends of the two sections. This strip has its upper face formed with transversely extended recesses 11 and therefore the strip may constitute a rack upon which toilet articles, such as nail 70 files and the like may be placed and prevented from moving out of a desired position upon the top of the dresser. At the back of the dresser I have provided mirrors 12 which are stationary and project upward- 75 ly from the dresser at substantially right angles to each other. The mirrors 12 extend parallel to the side sections 2 and 3 of the dresser so that a person standing in front of the dresser may obtain either a 80 front view or a side view. I have also provided mirrors 13 which are disposed vertically at the forward corners of the body and pivotally connected thereto by hinges 14. By referring to Figure 4 it will be seen that 85 each hinge comprises companion leaves 15 and 16 having hinged ears 17 through which a pin 18 passes so that when a leaf 15 is secured to a corner post of the dresser body and a leaf 16 secured to a mirror, the mirror 90 will be hingedly mounted and may be swung from the position shown in full lines in Figure 3 to that indicated by dotted lines. It should be noted however, that when a mirror is swung outwardly from a position indicated by dotted lines in Figure 3 to the position indicated by full lines, the leaf 16 of a hinge will contact with the leaf 15 and prevent further movement of the mirror in this direction. Therefore, the mirror can 95 100

not be swung away from the front of the dresser body beyond the position shown in full lines in Figure 3 and there will be no danger of its striking the end of the dresser body and becoming broken by the force of the blow which would be received. It will also be noted that the forward corners of the top of the body are recessed as shown at 19 so that the mirrors may enter the recesses 5 when swung towards the front of the body. When the mirrors enter the recesses they contact with the walls thereof and forward faces of the corner posts 4, thereby limiting their forward movement and preventing 10 them from being swung past the position indicated by dotted lines in Figure 3. By this arrangement the mirrors 13 may be angularly adjusted and a person dressing in front of the dresser may obtain a back view. The mirrors have been extended above the 15 body of the dresser so that they may reflect from the mirrors 12 and thereby permit a view to be obtained from all angles.

Having thus described the invention, I 20 claim:

A dresser comprising a body having side portions extending transversely from each other, a top for said body consisting of sections having inner ends meeting at the intersection 25 of the side sections of the body, and a strip extending longitudinally of the meeting ends of the top sections in bridging and covering relation thereto and having its upper face formed with transversely extending recesses constituting seats for articles placed upon said top.

In testimony whereof I affix my signature.
